REFUSE BAG

George W. Poppe, Brooklyn, N. Y., assignor to
 Equitable Paper Bag Co., Inc., Brooklyn, N. Y.,
 a corporation of New York

Application June 20, 1934, Serial No. 731,426

6 Claims. (Cl. 229—53)

This invention relates to refuse bags and the principle object thereof is to so construct such a bag that it may be conveniently used for the purpose intended and which may be rapidly and inexpensively made by methods adapting it to be made by ordinary bag machinery.

Refuse bags are coming more and more into common use, especially in cities where apartments particularly are frequently equipped with incinerators. It is therefore much more convenient to deposit garbage or waste paper in a bag and pass it into the incinerator than it is to empty the refuse directly into the incinerator from a can or waste basket. The bag of the present invention is adapted to be placed in a waste basket or in a garbage can and to be conveniently held therein with the mouth of the bag held open for convenient use. When an ordinary bag is used as a refuse container it frequently happens that the mouth of the bag becomes partially closed, making it necessary to use two hands when something is to be placed in the bag. The bag of my present invention overcomes this difficulty and one of the features resides in the provision of an open mouth bag having slits spaced at intervals about the mouth whereby the top of the bag may be folded down over the edges of a waste basket or other refuse-receiving receptacle.

Another feature of the invention relates to the way in which the slits are placed thereby adapting the bag to be made by inexpensive methods and at a high rate of speed.

Further features and advantages will become apparent from the following description and claims when taken in connection with the accompanying drawings in which:

Figure 1 is a perspective view of the bag;

Figure 2 is the bag opened out in readiness to be inserted in a garbage can or waste basket or other refuse container;

Figure 3 is a diagrammatic illustration of the manner in which the web is cut, pasted and folded;

Fig. 4 is a more or less schematic view in longitudinal section of a bag machine adapted to more fully illustrate the method of producing my improved bag; and

Figure 5 is a section on the line 5—5, Figure 4, showing the arrangement of the dies for properly slitting the web.

Referring to Figure 1, the bag is primarily a bellows bag having a front wall 1, a rear wall 2 and bellows folds indicated at 3. The bottom

of the bag is folded over and pasted in the usual manner as indicated at 4.

A distinguishing feature of a bag of my invention over an ordinary bellows bag is the fact that the mouth of the bag is slit at intervals so that the top of the bag may be folded over to form a collar which will support the bag inside a refuse container. In order that such folding over may be conveniently accomplished the bellows folds are slit at 5 and 6. The front wall of the bag is slit at 7, each of the slits extending from the mouth of the bag to a scored line indicated at 8, this line making it more convenient to fold the upper portion of the bag back to form a collar. In the back wall an unpasted portion of the usual seam serves the purpose of a slit.

In ordinary bellows bags the back wall contains a seam. For convenience of manufacture in the present instance I leave a portion of this seam unpasted, the unpasted portion extending from the scored line 8 to the mouth of the bag as indicated at 9, Figure 2. This method of leaving a portion of the rear wall open is equivalent to slitting but is much more convenient in manufacture as will more clearly appear when the method of making a bag is described.

The bag of my present invention is preferably made on an ordinary bag machine and the general method of making a bellows bag is followed with such modifications as I will now describe.

Referring to Figure 3, a web of paper indicated generally by reference character 12 is fed from a roll 14 and after passing over suitable guiding rollers passes over the upper roller 15 which reverses its direction of movement. From the roller 15 the web passes under a former indicated at 16 about which the web is folded to form a bellows tube by means well known in the art. In order that the bag may be substantially square when opened, the bellows folds are made so deep that they meet in the center or very nearly meet. If a bag somewhat rectangular in shape is desired, of course the bellows folds 40 would not be made so deep. This, of course, is a matter of choice and has no special significance insofar as the present invention is concerned.

As the web of paper passes over the roller 15, 50 the various slits are made in it. These slits are made by dies carried on the shaft 18, Figures 4 and 5, the said shaft being driven from a sprocket chain 19 which through gears and sprocket chains well known in the bag machine art derive their 55

motion from the lower pinch bar shaft 20. The shaft 18 carries three dies, 21, 22 and 23. The die 22 makes the slit 7 which is central of the web, while the dies 21 and 23 make the slits 5 and 6, the slits 5 and 6 being of equal length but the slit 7 being slightly shorter.

It is customary in making an ordinary bellows bag to apply a line of paste to one edge of the web prior to folding the same. In the present instance I modify this method somewhat and instead of applying a continuous line of paste to the edge of the web I apply paste at intervals, there being gaps in the paste line, which gaps correspond to the unpasted portion 9 of the rear wall of the bag as shown in Figures 1 and 2. Two of these gaps are indicated at 9 in Figure 3, one gap appearing in the web in line with the slits and another in the tube, as shown in the same figure. A third gap is between the two shown but is hidden by the fold of the web. It follows from this method of pasting that while the entire rear wall of the bag below the scored line 8 is pasted, that portion above the scored line is unpasted. This method of applying the paste is illustrated more clearly in Figure 4 where the paste disc 24 is provided with a cutout portion 25. The size of the disc, of course, must be such that the paste-applying portion of its periphery is equal to the length of the seam which is to be pasted while the cutout portion 25 is equal to the gap that is to be created in the paste line. The disc 24 must also be correctly timed and therefore it is positively driven. This is accomplished by means of a sprocket chain 26 passing over a sprocket, not shown, but which is secured to the shaft 28. The shaft 28 is geared in a one-to-one ratio with the pinch bars 20 which, as is well known in the bag machine art, make one rotation for each bag made. Therefore the paste-applying disc 24 will rotate in the same ratio.

The web, after being folded about the former and formed into the bag tube, is drawn along by the usual feed rollers 30. The edge of the former is serrated at 32 and there is the usual lip knife 34 for cutting the bag tube into bag lengths, this operation being effected through the medium of the pinch bars 20 which momentarily retard the tube at the instant that the striker bar 36 delivers a sharp blow to the tube from beneath.

After a bag section is severed from the bag tube and at the instant that the pinch bars free it, the bag tube is pulled forward by scoring rollers 38. The bag then passes to the usual cylinders 40 which fold and paste the bottom after which the bag passes under a guide roller 42 and between other scoring rollers 44. The rollers 38 form the score line 10 while the rollers 44 form the score line 8 as will be readily understood. 46 represents a paste supply roller from which paste is wiped off by the paste bar 47 to apply a line of paste to the bag bottom as is common in bag machines.

65 The scoring rollers 38 and the cylinders 40, together with the scoring rollers 44, guide rollers 42 and paste-applying roller 46, are mounted on a carriage which may be adjusted by means of a rack 48 engaged by pinion 49. This mechanism is also common in bag machines and is for the purpose of making adjustments for different bag lengths and need not be described in further detail.

From the foregoing it will be apparent that 75 the bag is formed by slitting a web of paper at

three points transversely of the web, folding the web to form a bellows bag tube with the inner edge of each bellows fold coincident with one of the slits. This will be clearly apparent from Figure 3. The method further consists in applying a line of paste at intervals to the edge of the web but leaving gaps in the paste line. The timing of the folded tube is such that the gap in the paste line of each tube is located adjacent to the bag mouth as also indicated in Figure 3. 10

The score line 10 is for the purpose of making it more convenient to square the bag bottom prior to inserting it in the refuse container and this score line may be omitted if desired.

By reason of the method employed, the bag of 15 my present invention may be made on an ordinary bag machine at high speed and with no waste of paper.

The leaving of a portion of the seam line unpasted serves the purpose of a slit and has the 20 further advantage that all of the slits which are necessary in the practice of my present method can be made in the web. If an attempt were made to slit the rear wall of an ordinary bellows bag tube the slit would pass through the pasted 25 portion. Such a slit would moreover have to be made after the tube were formed which is not so convenient a method as slitting in the web.

What I claim is:

1. A refuse bag consisting of a bellows folded 30 tube having a closed bottom and open mouth, the bellows of which are so folded as to produce a substantially square bottom when opened out, the mouth of the bag having slits in the walls thereof and along lines coincident with the bellows folds, thereby permitting the top of the bag to be folded back to form a collar that may overlap the edge of a receptacle in which the bag is adapted to be placed.

2. A refuse holder consisting of a bag having 40 a front wall, a seam wall and a bellows fold between said walls, a transverse score line spaced from the mouth of the bag, said front wall and the inner fold of said bellows being slit from the mouth of the bag to said score line.

3. A refuse holder consisting of a bellows bag having a front wall and a rear or seam wall, a slit in the front wall and slits in the inner fold of each bellows, said slits extending from the mouth of the bag downwardly a distance sufficient to permit the bag when opened out to present a flat bottom and to permit the top to be folded over to form a collar to support the bag in position within a receptacle.

4. A bellows bag having a slotted front wall 55 and a seam wall, the seam of which is unpasted for a distance extending from the top edge of the bag to a point coincident with the lower end of the slit in the front wall.

5. A bellows bag having a slotted front wall, 60 slotted bellows the latter slits being at the inner fold of the bellows and a seam wall, the seam of which is unpasted for a distance extending from the top edge of the bag to a point coincident with the lower ends of the other slits.

6. A bellows bag having a front wall and a seam wall, a bellows fold between said walls, a transverse score line spaced from the mouth of the bag, said front wall and the inner fold of said bellows being slit from the mouth of the bag to said score line and said seam being unpasted from the score line to the bag mouth, the remainder of the seam being unpasted.
